United States Patent Office

Des. 195,083
Patented Apr. 23, 1963

195,083
SCISSORS

George R. Stehl, New York, N.Y., assignor to Domus Products Inc., New York, N.Y., a corporation of New York

Filed Feb. 2, 1962, Ser. No. 68,620

Term of patent 14 years

(Cl. D22—5)

FIG. 1 is a top plan view of scissors showing my new design in partially open position;

FIG. 2 is a bottom plan view of the scissors in closed position;

FIG. 3 is a bottom plan view of the scissors in partially open position; and

FIG. 4 is an end view of the scissors looking from the left in FIG. 2.

FIG. 5 is an enlarged sectional view taken along the line 5—5 in FIG. 2.

I claim:

The ornamental design for scissors, substantially as shown.
